(57) **CLAIM**

The ornamental design for a hose connector door for a floor care appliance, as shown and described.

DESCRIPTION

FIG. 1 is a rear perspective view of a hose connector door for a floor care appliance showing our new design; FIG. 2 is a left side view thereof; FIG. 3 is a front view thereof; and, FIG. 4 is a right side view thereof.

The portion shown in dashed lines is shown for illustrative purposes only and forms no part of the claimed design.
